ROTARY PUMP

Laurits Dinesen and Lawrence J. Olson, Minneapolis, Minn., assignors to Perfection Manufacturing Corporation, Minneapolis, Minn., a corporation of Minnesota

Application February 24, 1948, Serial No. 10,534

2 Claims. (Cl. 103—136)

1

Our invention relates to rotary pumps of the reciprocating vane type and, more particularly, to pumps of the stated type involving reciprocating vanes of resilient material such as rubber or synthetic rubber.

The primary object of our invention is the provision of a pump of the character described, which is capable of producing relatively high fluid pressures. In accordance with the invention, this is achieved inexpensively by a novel design of reciprocating vane, producing an improved fluid pressure seal between the reciprocating vanes and the cooperating wall of the pump chamber.

Another important object of our invention is the provision of a pump having a relatively permanent rotor having readily replaceable, inexpensive vanes therein.

Another object of our invention is the provision of a novel sealing means for the rotary shaft.

The above and still further objects of our invention will become apparent from the following detailed specification, appended claims, and attached drawings.

Referring to the drawings, wherein like characters indicate like parts throughout the several views:

Fig. 1 is a view in end elevation of our novel pump;

Fig. 2 is an enlarged end elevation of our novel pump with one of the end wall elements removed;

Fig. 3 is an enlarged vertical section taken on the line 3—3 of Fig. 1;

Fig. 4 is a horizontal section, taken substantially on the line 4—4 of Fig. 1;

Fig. 5 is a view in elevation of the interior of one of the end wall elements;

Fig. 6 is an enlarged axial section through a sealing member used in accordance with our invention; and

Fig. 7 is a view corresponding to Fig. 2, but showing a slightly modified form of our invention.

Referring to Figs. 1 to 6 inclusive of the drawings, the numeral 1 indicates, in its entirety, a pump housing preferably metallic in nature. The housing 1 defines a cylindrical chamber 2, the circular wall of which is indicated by the numeral 3. A pair of end wall elements 4 define end walls 5 of the chamber 2 and are provided with inlet and outlet recesses 6 and 7 respectively. The housing 1 is further provided with opposed bosses 8 and 9 respectively which are threaded to receive fluid conduit means in the nature of pipes or the like 10, and which define inlet and outlet passages 11 and 12 respectively. As shown, particularly by reference to Fig. 4, the inlet passage

2

11 is bifurcated to provide communication with the recesses 6 in the end wall elements 4. The outlet passage 12 is similarly divided to provide communication therebetween and the recesses 7 in the end wall elements 5. It will be noted that the recesses 6 and 7 communicate with the cylindrical chamber 2 and form a passage therebetween and the inlet and outlet passages 11 and 12 respectively. It will be further noted that the inlet and outlet passages 11 and 12 are circumferentially spaced about the axis of the cylindrical chamber 2 and are in axial alignment one with the other. The end wall elements are secured to the body 1 by machine screws or the like 13, and sealing gaskets 14 are interposed between the main body 1 and the end wall elements 4.

A rigid rotor element 15, also preferably formed from metal or the like, is mounted for rotation within the chamber 2 by means of a shaft 16, fast therein, and journaled in opposed bearing bosses 17 of the end wall elements 4. It will be seen, particularly by reference to Figs. 2 and 3, that the rotor 15 is eccentrically disposed with respect to the chamber 2 and that opposite side surfaces 18 thereof have close working engagement with the inner surfaces or end walls 5 of the end wall elements 4.

The rotor 15 is provided with a plurality, shown as being four in number, of circumferentially-spaced radially-extended channels 19, in each of which is mounted for radial sliding movements a preferably flexible resilient vane 20 having at its radially outer end, a lip 21 which projects angularly therefrom in the direction of rotation of the rotor. The inner and outer surfaces 22 and 23 respectively of the lip 21 converge toward the forward edge thereof, the inner surface 22 being relatively flat and at substantially right angles to the body of the vane 20, and the outer surface 23 thereof being cross-sectionally arcuate in form—the arc thereof corresponding substantially to the arc of the circular wall 3 of the chamber 2.

It will be observed, particularly by reference to Fig. 2, that, at its periphery, the rotor 15 is provided with a plurality of relatively flat surfaces 24, one each of which extends between outer ends of adjacent channels 19. It will further be observed that, preferably and as shown, the walls of the channels adjacent the lips 21 are of less height than the opposing walls of said channels, said higher wall of each channel 19 backing up and supporting the resilient vanes 20 and preventing undue distortion thereof.

While the invention can be successfully practiced with a cross-sectionally circular rotor, providing convex arcuate surfaces intermediate the vanes 20, we have found, in practice, that greater efficiency can be obtained by diametrically reducing the segments of the rotor intermediate the adjacent vane-containing channels 19 to thereby increase the chamber spaces between adjacent vanes 20 and beneath the forwardly-projecting lips 21 thereof. In the preferred embodiment of the invention, this is accomplished by providing the rotor with flat surfaces 24 intermediate adjacent vane channels 19. In either event, however, it should be obvious that fluid drawn into the chambers 21, between the vanes 20 from the inlet passages 11, has an initial impact of considerable force against the inner surfaces 22 of the lips 21, thereby forcing the lips 21 and vanes 20 radially outwardly to cause the arcuate surfaces 23 of the lips 21 to make tight sealing engagement with the chamber wall 3. It will be clear that fluid pressure built up within the chamber 2' between the vanes 20 will be applied to only the inner surfaces 22 of the vane lips 21 and in a generally radially outward direction which will serve to force the lips 21 and vanes 20 radially outward into tighter sealing contact with the cylindrical wall 3 of the pump chamber 2 as the pressure increases. In short, the pressure within the chambers 2' is utilized to increase the sealing pressure between the vanes 20 and the wall 3.

It will be observed that the opposed end wall elements or caps 4 are provided with annular recesses 25 which are concentric with the shaft 16 and terminate in flat end walls 26. Contained within each of the recesses 25 is a bushing or sleeve 27. The sleeve 27 may be made of any suitable flexible resilient material, such as synthetic rubber or the like, and is provided at one end with a radially-projecting circumferentially-extended flange 28 which is preferably integrally formed therewith. The sleeves 27 are of a size to fit snugly on the shaft 16 so as to rotate therewith, and have their ends opposite the flange 28 abutting the opposed side surfaces 18 of the rotor 15. The bushings 27 are of greater length than the distance between the flat end walls 26 of the recesses 25 and the side surfaces 18 of the rotor 15. It will be seen, particularly by reference to Fig. 6, that the flanged ends of the bushings 27 are provided with concave faces 29 which are disposed adjacent the end walls 26 of the recesses 25. When the end wall elements 4 are pulled tightly against the main body 1, the flanges 28 of the bushings 27 are forced in a direction axially of the bushing to a point where the concave surfaces 29 are compressed against the flat end walls 26 of the recesses 25. Fluid within the pump which might enter the recess 25 under pressure will tend to force the flanges 28 against the end walls 26, whereby to still further seal the interior of the pump from leakage around the shaft 16.

While we have shown the recesses 25 as being formed in the end wall elements 4, it should be clear that suitable recesses could be provided in the rotor element 15. The important thing is that the depth of the recesses 25, irrespective of whether it be located in the rotor element 15 or in the side wall element 4, is slightly less than the maximum length of the resilient bushing 27, corresponding approximately to the minimum length thereof, measured along the shaft 16.

In the modified form of the invention, illustrated in Fig. 7, the pump housing, inlet and out-

let bosses thereon, fluid conduit means leading thereto and therefrom, and rotor chamber are all identical to the structure illustrated in Figs. 1-6 inclusive and bear the same reference characters with prime marks added. The structure of Figs. 1-6 inclusive illustrates a unidirectional pump, whereas Fig. 7 illustrates a pump that may be run in either direction. In the pump of Fig. 7, we provide a rotor 30 fast on a shaft 31 journaled in end wall elements in the manner of the structure of Figs. 1-6 inclusive and having a plurality of radially outwardly-opening axially extended channels 32 therein. Mounted for radial sliding movements in each of the channels 32 is a flexible resilient vane 33 provided at its outer end with a pair of opposed flexible resilient lips 34 which project angularly therefrom in the same manner as the lips 21 of the vanes 20, illustrated in the preferred embodiment of the invention. The rotor 30 is shown as having flat peripheral surfaces 35; and the medial plane of each channel 32 extends through the point of intersection of two adjacent of the flat surfaces 35. The action of the pump of Fig. 7 is identical to that of Figs. 1-6 inclusive and only one lip 34 of each vane 33 will be utilized at any particular time for sealing engagement with the chamber wall 3', the lip so utilized being the one which projects forwardly in the direction of rotation of the rotor 30.

As is necessary with pumps of the type herein set forth, provision is made for displacement of fluid in the channels 19 radially inwardly of the vanes 20. This provision is in the nature of a plurality of passages 36 extending diametrically through the rotor 15 and shaft 31 and connecting diametrically opposite channels 19. Radially inward movement of any one of the vanes 20 and corresponding radially outward movement of the opposed vane 20 will cause the fluid in the channel 19 of one thereof to flow through the passages 36 connected therewith to the channel 19 of the other thereof. Thus, impedance of radial movements of the vanes 20, due to differential and pressure within the channels 19, is eliminated.

Our invention has been thoroughly tested and found to be entirely satisfactory for the accomplishment of the objectives set forth; and, while we have shown a preferred embodiment and a single modification of our invention, it will be understood that the same is capable of further modification without departure from the spirit of the invention as defined in the claims.

What we claim is:

1. In a device of the class described, a housing having a cylindrical pump chamber therein, circumferentially-spaced inlet and outlet passages leading respectively to and from said chamber, a rotor journaled in said housing and eccentrically positioned within said chamber, a plurality of circumferentially-spaced radially outwardly-opening channels in said rotor, and a vane loosely mounted in each of said channels for radial sliding movements, the peripheral surfaces of said rotor intermediate said channels being flat, the rear walls of said channels with respect to the direction of rotation of the rotor being higher than the front walls thereof.

2. The structure defined in claim 1 in which said vanes at their radially outer ends are provided with integral rubber-like lips which project angularly therefrom in the direction of rotation.

Laurits DineSEN.
